[57] **CLAIM**

The ornamental design for a baton, as shown and described.

DESCRIPTION

FIG. 1 is a perspective view of a baton showing my new design;

FIG. 2 is an enlarged side elevation of the ball end of the baton of FIG. 1; and

FIG. 3 is a top plan view of the ball of FIG. 2.

The balls at each end of the baton are identical in appearance, but not in size.

FIG. 2

FIG. 3

FIG. 1
